HAND PRINTING DEVICE

Clarence C. Ruebel, Fort Dodge, Iowa

Application June 7, 1945, Serial No. 597,997

17 Claims. (Cl. 101—260)

1

This invention relates to hand type printing devices for producing imprints from galleys of type. More particularly the invention is directed to printing devices for producing a continuous strip containing a series of names and addresses for use in connection with mailer addressing machines, or for printing of proof sheets. Generally, such printed matter is produced in extremely limited quantities, that is, either a single copy or relatively few copies are produced at one time. To produce one or a relatively few copies of such printed matter on a conventional printing press, in addition to being time consuming, is a relatively expensive operation, and hence for such purposes hand printing has usually been resorted to.

The usual procedure followed in hand printing address lists, is to set up galleys of type, usually in columnar form, and such galleys of type are permitted to remain set up over long periods of time, and are altered only when necessary to add new addresses or change existing addresses. In practice, the galley of type is first coated with suitable ink, by usual methods, and a dampened sheet or strip of paper is then placed over the inked galley of type for transferring the imprint of the type thereto by means of a platen block. Generally the sheet of paper is of a width corresponding to the total width of all of the type set up in the galley, often comprising several columns of individual names and addresses. The sheet or sheets thus printed are then cut into strips containing single columns or lists of names and addresses, and the strips are trimmed and pasted together to form a continuous tape which is then wound into a roll and used in connection with a "Wing-Horton" or "Dick" type of mailer. By virtue of such mailers the roll of paper tape containing the list of addresses is then severed into individual address slips and applied to individual mailing pieces.

The printing device embodying the present invention comprises a storage roll of paper tape adapted to be trained over an impression roller and having the free end thereof attached to a rewind spool on which the printed tape is adapted to be wound. The device, as shown, is constructed and arranged for single column printing onto the paper tape, which it may be understood is of a suitable width for a single address. In the use of the device the galleys of type are first inked in the usual manner, and the device is moved over the type in a manner so that the impression roller, with the web of paper tape trained thereover, is caused to be drawn

2

over each single column of the galley of type so as to produce a continuous tape containing the entire series of addresses.

This invention also contemplates the provision, in a hand printing device, of a novel means and arrangement for effecting transfer of ink to the continuous paper tape by means of an ink-containing ribbon trained around the impression roller, in superimposed relation to the paper tape, and adapted, when the device is moved over the type, to be brought into direct contact with said type for effecting an imprint transfer to the tape.

I am aware of one prior construction by virtue of which single column printing is effected upon a continuous web of paper tape and which construction is disclosed in the Millsap Patent No. 1,338,642 dated April 27, 1920. The construction disclosed in this patent is relatively complicated, cumbersome, somewhat awkward to use, and comparatively expensive.

One of the objects of the present invention is to provide a novel hand printing device of the character indicated which is relatively simple in construction, light in weight, adapted to be easily and efficiently used, and capable of being economically manufactured.

Another object is to provide an improved printing device of the character indicated wherein the impression roller is flexibly mounted so as to readily adapt itself to the surface contour of the galleys of type, and thus insure obtaining uniform and clear imprints from the type.

A further object is to provide, in a device of the character indicated, an improved drive arrangement between a storage reel of paper tape and a rewind spool onto which the printed tape is adapted to be wound.

Still another object is to provide an improved printing device of the character indicated, having a pair of hand grips disposed laterally of and in substantial alignment with the axis of rotation of the impression roller for insuring adequate pressure of the impression roller against the type of the galleys for producing sharp and clear imprints from the type.

A still further object is to provide an improved printing device of the character indicated wherein the ink applying means comprises an ink-containing ribbon disposed in overlying relation to the paper tape, at the area of contact of said tape with the impression roller, whereby movement of the device over a galley of type causes an imprint of the type to be transferred

through the inked ribbon for printing directly upon the paper tape.

Other objects and advantages of this invention will be apparent from the following description, taken in connection with the accompanying drawings in which:

Figure 1 is a plan view of a printing device embodying the present invention;

Figure 2 is a front elevational view of the device;

Figure 3 is a view in side elevation, partly in section, taken substantially as indicated at line 3—3 of Figure 2;

Figure 4 is an enlarged view taken substantially as indicated at line 4—4 on Figure 3, but with the impression roller shown in elevation;

Figure 5 is an enlarged transverse sectional view through the device, taken as indicated at line 5—5 on Figure 3;

Figure 6 is an enlarged fragmentary view of the support arms for the storage reel and rewind spool, together with the latch means therefor, taken substantially as indicated at line 6—6 on Figure 2;

Figures 7 and 8 are exploded views of the storage reel and supporting arm, and the rewind reel and supporting arm, respectively;

Figure 9 is a fragmentary view of a portion of the printed paper tape as produced by the device embodying the present invention;

Figure 10 is an enlarged side elevational view with parts in section at approximately the longitudinal central plane thereof, and provided with the ink-containing ribbon and auxiliary apparatus for effecting transfer of ink to the paper tape;

Figure 11 is a staggered view, part in section and part in elevation, taken substantially as indicated at line 11—11 on Figure 10;

Figure 12 is a vertical section through the ink-containing ribbon supporting and guiding apparatus, taken substantially as indicated at line 12—12 on Figure 10.

The device embodying the present invention includes a transversely disposed main frame 10 of elongated form. Said main frame is preferably formed as a sheet metal stamping, and includes, at opposite sides, a depending flange 11. The central portion of said frame is cut away to form a rectangular opening, and the material from said opening is bent upwardly to form a pair of transversely spaced apart mounting flanges 12. Journaled in said flanges 12 are two shafts 14 and 15 disposed approximately parallel and spaced apart in a longitudinal direction. Rigidly connected to corresponding ends of the respective shafts are upwardly extending supporting arms 16 and 17. Rigidly attached to the upper end of the arm 16 is a horizontally extending shaft 19 on which is adapted to be removably mounted, for free rotation thereon, a core or spool 20, onto which the printed tape is adapted to be rewound in roll form, as indicated at 21 in Figure 8. The core 20, at the end adapted to be positioned adjacent the arm 16, is formed with an annular groove as indicated at 23.

The upper end of the arm 17 has rigidly attached thereto a horizontally extending shaft 25 adapted to have removably mounted thereon and freely rotatable therewith a core 27 of a storage reel. Rigidly connected to said core 27 is a disc 29 adapted to be positioned adjacent the arm 17 when said core 27 is positioned on said shaft 25, so that the marginal edge of the disc 29 is seated in the groove 23 of the core 20 of the rewind spool, as will hereinafter be described.

The ends of the shafts 14 and 15, opposite the supporting arms 16 and 17, are each provided with collars 31 having outwardly extending set screws 32 to which are connected the opposite ends of a tension spring 34, which tends to urge the shafts 14 and 15 in a direction for causing the arms 16 and 17 to move toward each other. The lower end of the arm 16, as may be clearly seen in Figure 6, is formed so that the said arm may move in a clockwise direction, with respect to the showing in said Figure 6, to only a limited extent because the lower end of said arm will be brought into abutting engagement with the upper surface of the main frame 11. The lower end of the storage reel supporting arm 17 is formed with adequate clearance so that said arm may be moved in either direction, except that when moved outwardly it will be against the reaction of the spring 34. Mounted on the core 27, in fixed relation thereto, such as by a friction fit, or keying features, not shown, is a storage roll of paper tape as indicated at 35.

By means of spring 34 acting on said arms 16 and 17, the disc 29 with which the storage roll of tape 35 is associated, is urged into firm seating engagement with the groove 23 of the core of the rewind spool so that upon rotation of said disc 29, with the roll of tape 35, as will hereinafter be described, the core or spool 20 will be caused to rotate in a direction opposite to the direction of rotation of said disc for rewinding said tape into a roll as indicated at 21 in Figure 8 of the drawings.

To maintain the arms 16 and 17 in proper relation to each other I provide a latch arm 36 mounted freely at one end on the shaft 14, and having a notch 37 in its lower edge adjacent the opposite end, located to cooperate with a headed stud 39 carried on the arm 17, as clearly seen in Figure 6 of the drawings. The latch member 36 is yieldingly urged to latching position by a spring 41 anchored on a bolt 43 carried on the adjacent upstanding flange 12 of the main frame, with the free end of the spring trained around the latching arm and seated in a notch 44 of said arm. By virtue of this arrangement the supporting arm 17 which provides support for the core 27, on which a storage roll of paper tape is adapted to be mounted, is held in relatively fixed position. Due however to the action of the spring 34 there is a tendency for the shaft 14 to rotate and move the arm 16, carrying the rewind spool thereon, in a direction to seat the groove 23 of the core or spool 20 firmly against the edge of the disc 29 of the storage reel so that the storage reel and rewind spool are yieldingly maintained in driving, frictional relationship to each other.

Mounted between the side flanges 11 of the main frame is a rectangular shaped auxiliary frame 47 in which is journaled the stub ends 48 of an impression roller or platen 50, as seen in Figure 4. The impression roller preferably is of resilient material such as rubber, and of a consistency approximating that of a typewriter platen roll. The auxiliary frame is mounted in place within the main frame so as to dispose a portion of the roller below the main frame, as clearly seen in Figures 2, 3 and 4 of the drawings, by a pivoted connection of said auxiliary frame to the side flanges 11 of the main frame by a pair of bolts 51 so that the axis of the roller 50 is disposed approximately parallel to the axes of the storage reel and the rewind spool. The pivotal mounting for the auxiliary frame, carrying said

roller 50, is preferably at substantially the medial longitudinal plane of the device.

The laterally extending end portions of the main frame are provided with suitable hand grips, shown in the form of a pair of upstanding handles 52, rigidly attached to said main frame by means of screws 53, as may be seen in Figure 3 of the drawings. These handles provide a convenient manner of gripping and supporting the device for movement over the galley of type, as indicated at "A," in a manner to insure obtaining a clear and sharp imprint onto the paper tape.

The paper tape, as indicated at 35a, is trained off of the storage roll 35 and extends downwardly into a guide chute 55, of generally flattened rectangular cross section. Said chute is rigidly attached to the auxiliary frame 41, as may be clearly seen in Figures 3 and 10 of the drawings, so that said tape is caused to be properly guided and trained around the underside of the impression roller 50. Said tape extends from said roller 50 in an upwardly direction, and is attached to the rewind spool 26 by folding an end portion of the tape beneath the free end of an arcuate plate or clip 57 on said rewind spool, as seen in Figure 10. Thus said chute swivels with the auxiliary frame 41, and insures proper aligned feeding of said paper tape around the impression roller at all times, and avoids possible bulges or buckling of the tape, which would result in improper and unclear printing thereon.

In using the device a galley of type as indicated at "A" in Figures 2 and 3 of the drawings is first inked in a conventional manner, and the device is then moved over a single column of type by grasping the handles 52 and exerting a downward pressure to cause the impression roller 50 with the paper tape 35a below to firmly contact the type. By moving the device forwardly over the column of type, the friction created by the pressure imposed by the impression roller against the paper and thence against the type causes the paper tape to receive the ink imprint from the galley of type and simultaneously unwind the tape from the storage roll 35, and due to the frictional drive between the disc 29 of the storage roll and the groove 23 of the rewind spool, said rewind spool is rotated in an opposite direction to the direction of rotation of the storage reel, as clearly seen in Figure 3 of the drawings, and thus causes winding of the printed tape onto the rewind spool in the form of a roll. Thus the device may be moved over a series of columns of type to produce a continuous printed web of paper tape containing a series of individual addresses. After a complete printing of all of the addresses the rewind spool may be rotated a slight amount so that the last printed addresses may be wound onto the rewind spool, and the paper tape may then be severed below the rewind spool. The roll 21 containing the continuous list of printed addresses, may then be utilized in connection with conventional mailer devices such as the "Wing-Horton" or "Dick" type mailers for severing the tape into slips containing individual addresses for application to individual pieces of mail or other articles to be addressed. The core 20 of the rewind spool may then be replaced on the shaft 19 and the free end of the tape again attached thereto for repeating the operation.

By providing a pivotal mounting of the auxiliary frame 41, with respect to the main frame 40, insures accommodation of the impression roller and tape thereon to the contour of the upper

surface of the type of the galley, to obtain clear, sharp imprinting onto the tape. As above mentioned, buckling of the paper tape in passage around the underside of the roller is avoided by reason of the guide chute 55 being rigidly attached to the auxiliary frame so that said chute moves with the auxiliary frame, and thus the paper tape is caused to be in true alignment with the impression roller.

10 The latch feature above described, for supporting the arm 17 and storage reel in a relatively fixed, upright position permits quick and easy disengagement of said arm so that it may be swung downwardly to the dot and dash position indicated in Figure 3 of the drawings for convenience in replacement of a storage roll of paper tape, and when said arm is moved to such position the arm 16 carrying the rewind spool follows it for a short distance until the lower end 15 of said arm 16 abuts against the top of the main frame 40. When the arm 17 is again moved back to normal position the latch member 36 automatically engages the stud 39 for locking the arm 17 in upright position, and the disc 29 engaging in groove 23 of the rewind spool causes the arm 16 and rewind spool to again assume the position seen in Figure 3 of the drawings.

In Figures 10, 11 and 12 I have shown apparatus attached to the printing device which eliminates the necessity for inking the type of the galley. As shown, supporting brackets 70 and 71 extend fore and aft with respect to the main frame 41, the supporting bracket 70 being directly connected to the auxiliary frame 41 and the bracket 71 being directly connected to the guide chute 55, as clearly seen in Figure 10 of the drawings. Journaled in the outer end of the bracket 70 is a rewind spool 73, and journaled in the outer end of the bracket 71 is a storage spool 74 containing a continuous strip of ink-containing ribbon 75, such as a cash register type of ribbon, which ribbon is adapted to be trained downwardly from the storage spool 74 into direct contact with the paper tape 35a at the underside 30 of the impression roller, and is trained upwardly and connected to the rewind spool 73. To insure minimum surface contact of the inked ribbon 75 with the paper tape 35a I provide a pair of idler rollers 77 mounted on depending arms 78a and 78b of said brackets 70 and 71, respectively. These idler rollers position the ink-containing ribbon in a manner so as to obtain a relatively small amount of surface area contact of the ribbon with the paper tape.

40 55 The rewind spool 73 is attached to a shaft 80 by pins 81, and the shaft being journaled at opposite ends in the bracket 70. One end of said shaft 80 is fixedly mounted on a pulley 82 having a V-shaped peripheral groove in which is seated a V belt 83 which is also trained around a corresponding pulley 85 fixedly mounted on the corresponding end of a shaft 86 of the storage spool. Said shaft is supported at opposite ends in the bracket 71 and has the storage spool 74 rigidly attached thereto by means of pins 87. Rigidly mounted on said shaft 86 on the hub of the pulley 85 is a ratchet wheel 90 with which cooperates a pivoted detent 91 carried by the bracket 71, as clearly seen in Figures 10 and 11. The purpose of the detent is to permit free rotation of the storage spool in the direction to pay out the ink ribbon 75, and when it is desired to rewind the ribbon 75 off of the rewind spool 73, back onto the storage spool, I provide a hand crank 92 connected on the opposite end of the

shaft 86, and by disengaging the detent 91 said spool 74 may be rotated to rewind the ink-containing ribbon thereon.

It will now be apparent that when the printing device with the inking attachment thereon is drawn over a column of type of a galley, the type causes imprinting through the ink-containing ribbon 75 directly onto the paper tape 35a. Due to the downward pressure exerted through the handles 52, incident to forward movement of the device over the type during such printing operation, both the ink-containing ribbon and the paper tape are paid off of their respective storage spools 74 and 27. Due to the friction drive between the spools 73 and 74 in the form of the V belt 63, and to the frictional drive by engagement of the disc 29 of the paper tape storage reel in the groove 23 of the rewind spool 20, the ribbon and the paper tape are caused to wind onto their respective rewind spools.

The ink ribbon rewind spool is readily demountable from the bracket 70 by merely removing one of the pins 81 to facilitate threading of the paper tape through the guide chute 55 around the impression roller, thence in an upwardly direction for connection to the rewind spool 20. Likewise the storage spool 74 may be quickly and easily removed from the supporting bracket 70 by removal of the pins 87, in the event it is desired to replace the ribbon, so as to withdraw the shaft 86 to the dot and dash position shown in Figure 12. As above mentioned, however, the ribbon may be reused a number of times and may be rewound back onto the storage spool 74 as desired by merely disengaging the detent 91 and rotating the hand crank 92.

Although I have herein shown and described a preferred embodiment of my invention, manifestly it is capable of modification and rearrangement of parts without departing from the spirit and scope thereof. I do not, therefore, wish to be understood as limiting this invention to the precise form herein disclose, except as I may be so limited by the appended claims.

I claim:

1. A printing device of the character described, comprising a main frame; a storage reel of paper tape; a rewind spool; an impression roller carried on and extending below the lowermost portion of the frame, the frame being adapted for movement along a galley of type whereby said roller bears on the type and supports the frame thereby, said tape from the reel being trained around the underside of the roller and connected to said rewind spool; and friction drive means comprising cooperating elements on said reel and spool for causing rotation of the spool to wind said tape thereon in response to rotation of said reel, incident to unwinding of the tape from the reel, by movement of the roller and tape over a galley of type.

2. A printing device of the character described for use with a galley of type, comprising a main frame; a storage reel of paper tape; a rewind spool; the end of the tape being connected to said rewind spool; separate, upwardly extending arms for supporting said reel and spool, said arms being pivotally mounted at their lower ends on said frame; interengaging friction driving elements on said reel and spool; means acting on said arms for yieldingly maintaining said driving elements in operative engagement with each other, and means for unwinding the tape from said reel and bringing it into contact with

the type, whereupon the tape is rewound on said spool by rotation thereof.

3. A printing device of the character described for use with a galley of type, comprising a main frame; a storage reel of paper tape; a rewind spool; the end of the tape being connected to said rewind spool; separate, upwardly extending arms for supporting said reel and spool, said arms being pivotally mounted at their lower ends on said frame; interengaging friction driving elements on said reel and spool; means acting on said arms for yieldingly maintaining said driving elements in operative engagement with each other; means for detachably latching one of said arms in an upright relation to said frame, and means for unwinding the tape from said reel and bringing it into contact with the type, whereupon the tape is rewound on said spool by rotation thereof.

4. A printing device of the character described, comprising a main frame; a rotatable storage reel of paper tape; a rotatable rewind spool having driving connection with said storage reel; and an impression roller carried on and extending below the lowermost portion of the frame, said tape from the reel being trained around the underside of the roller and connected to said rewind spool, said main frame having portions extending at opposite ends of the impression roller; and hand grips on said extensions of the main frame in approximate alignment with the axis of rotation of said impression roller, said roller being adapted to bear on a galley of type and support said frame thereby, whereby when the frame is moved along the galley of type said roller is rotated, thereby unwinding the tape from the reel and rewinding it on the spool.

5. A printing device of the character described, comprising a main frame; a rotatable storage reel for paper tape mounted on the frame; a rewind spool mounted on the frame having driving connection with said reel; an impression roller having its axis extending in the direction of the axes of said reel and spool; the tape from said reel adapted to be trained under said roller and connected to said rewind spool, and means pivotally supporting said roller on the frame on an axis normal to its axis of rotation, with a portion of said roller projecting below the lowermost portion of said frame, said roller being adapted to bear on a galley of type and support said frame thereby, whereby when the frame is moved along the galley of type said roller is rotated, thereby unwinding the tape from the reel and rewinding it on the spool.

6. A printing device of the character described, comprising, a main frame; a rotatable storage reel of paper tape; a rotatable rewind spool having driving connection with said storage reel; an impression roller, said tape from the reel being trained around the underside of the roller and connected to said rewind spool; and an auxiliary frame for supporting said roller, pivotally connected to the main frame, on an axis normal to the axis of rotation of said roller, with a portion of said roller projecting below the lowermost portion of said main frame, said roller being adapted to bear on a galley of type and support said frame thereby, whereby when the frame is moved along the galley of type said roller is rotated, thereby unwinding the tape from the reel and rewinding it on the spool.

7. A printing device of the character described, comprising a main frame; a rotatable storage reel for paper tape; a rotatable rewind spool having

driving connection with said storage reel; an impression roller; an auxiliary frame for supporting said roller, pivotally connected to the main frame on an axis normal to the axis of rotation of said roller, with a portion of said roller projecting below said main frame, the tape from said reel adapted to be trained under the roller and connected to the rewind spool, said main frame having portions extending laterally at opposite ends of the impression roller; and hand grips on said portions of the main frame in approximate alignment with the axis of rotation of the roller, said frame adapted to be moved over a galley of type whereby the roller is rotated by contact with the type, thereby unwinding the tape from the reel and rewinding it on the spool.

8. A printing device of the character described, comprising a main frame; a storage reel for paper tape; a rewind spool; an impression roller; an auxiliary frame for supporting said roller, pivotally connected to the main frame on an axis normal to the axis of rotation of said roller, with a portion of said roller projecting below said main frame, the tape from said reel adapted to be trained under the roller and connected to the rewind spool, said main frame having portions extending laterally at opposite ends of the impression roller; hand grips on said portions of the main frame in approximate alignment with the axis of rotation of the roller; and friction drive means comprising cooperating elements on said reel and spool for causing rotation of the spool to wind said tape thereon in response to rotation of said reel, incident to unwinding of the tape from the reel, by movement of the roller and tape over a galley of type.

9. A printing device of the character described, comprising a main frame; a rotatable storage reel of paper tape; a rotatable rewind spool having driving connection with said storage reel; and an impression roller carried on and extending below the frame, said tape from the reel being trained around the underside of the roller and connected to said rewind spool; said frame adapted to be moved along a galley of type with the roller in engagement with the type, whereby said roller is rotated, unwinding said tape from said reel and rewinding it on said spool; and upwardly extending guide means for directing the tape from said reel to said impression roller.

10. A printing device of the character described, comprising a main frame; a rotatable storage reel of paper tape; a rotatable rewind spool having driving connection with said storage reel; an impression roller; an auxiliary frame for supporting said roller, pivotally connected to the main frame on an axis normal to the axis of rotation of said roller, with a portion of said roller projecting below said main frame, the tape from said reel adapted to be trained under the roller and connected to the rewind spool, said main frame having portions extending laterally at opposite ends of the impression roller; hand grips on said portions of the main frame in approximate alignment with the axis of rotation of the roller; and upwardly extending guide means rigidly connected to the auxiliary frame and serving to guide the paper tape from said reel to said impression roller, said frame adapted to be moved along a galley of type with the roller in engagement with the type, whereby said roller is rotated, unwinding said tape from said reel and rewinding it on said spool.

11. A printing device of the character described, comprising a main frame; a rotatable

storage reel of paper tape; a rotatable rewind spool having driving connection with said storage reel; and an impression roller carried on and extending below the frame, said tape from the reel being trained around the underside of the roller and connected to said rewind spool, said reel and spool being simultaneously rotated to cause unwinding of the tape from the storage reel and winding it on the spool incident to rotation of the roller by frictional movement of the roller and tape over a galley of type; and inking means carried on the frame and progressively contacting said tape as it travels under the roller for causing an ink imprint of the type directly onto the tape incident to such movement of the roller over the galley of type.

12. A printing device of the character described, comprising a main frame; a rotatable storage reel of paper tape; a rotatable rewind spool having driving connection with said storage reel; and an impression roller carried on and extending below the frame, said tape from the reel being trained around the underside of the roller and connected to said rewind spool, said reel and spool being simultaneously rotated to cause unwinding of the tape from the storage reel and winding it on the spool incident to rotation of the roller by frictional movement of the roller and tape over a galley of type; and means carried on the frame for causing an ink imprint of the type directly onto the tape incident to such movement of the roller over the galley of type, said means comprising an ink-containing ribbon disposed in contact with the paper tape as it passes beneath the impression roller.

13. A printing device of the character described, comprising a main frame; a rotatable storage reel of paper tape; a rotatable rewind spool having driving connection with said storage reel; and an impression roller carried on and extending below the frame, said tape from the reel being trained around the underside of the roller and connected to said rewind spool, said reel and spool being simultaneously rotated to cause unwinding of the tape from the storage reel and winding it on the spool incident to rotation of the roller by frictional movement of the roller and tape over a galley of type; and means carried on the frame for causing an ink imprint of the type directly onto the tape incident to such movement of the roller over the galley of type; said means comprising a support having projections at opposite sides of the main frame; a storage spool of ink-containing ribbon mounted on one projection; a rewind spool for the ribbon mounted on the other projection; and drive means interconnecting said ribbon spools, whereby said ribbon is caused to be frictionally unwound from the storage spool and travel against the paper tape at the impression roller, and wound onto the rewind spool by the movement of the roller, with the paper tape and ribbon therebelow, over the galley of type.

14. A printing device of the character described, comprising a main frame; a rotatable storage reel of paper tape; a rotatable rewind spool having driving connection with said storage reel; and an impression roller carried on and extending below the frame, said tape from the reel being trained around the underside of the roller and connected to said rewind spool, said reel and spool being simultaneously rotated to cause unwinding of the tape from the storage reel and winding it on the spool incident to rotation of the roller by frictional movement of the

roller and tape over a galley of type; and means carried on the frame for causing an ink imprint of the type directly onto the tape incident to such movement of the roller over the galley of type; said means comprising a support having projections at opposite sides of the main frame; a storage spool of ink-containing ribbon mounted on one projection; a rewind spool for the ribbon mounted on the other projection; drive means interconnecting said ribbon spools, whereby said ribbon is caused to be frictionally unwound from the storage spool and travel against the paper tape at the impression roller, and wound onto the rewind spool by the movement of the roller, with the paper tape and ribbon therebelow, over the galley of type; and idler guides for said ribbon, carried by the support at a position to provide a practical minimum of continuous contact of the ribbon with the tape as they pass beneath the impression roller.

15. A printing device of the character described, comprising a main frame; a rotatable storage reel of paper tape; a rotatable rewind spool having driving connection with said storage reel; an impression roller; an auxiliary frame for supporting said roller, pivotally connected to the main frame on an axis normal to the axis of rotation of said roller with a portion of the roller projecting below the main frame, said tape from the storage reel being trained around the under portion of the roller and connected to the rewind spool, said reel and spool being simultaneously rotated to cause unwinding of the tape from the storage reel and winding it onto the spool incident to rotation of the roller by frictional movement of the roller and tape over a galley of type; and inking means mounted on the auxiliary frame and progressively contacting said tape as it travels under the roller for producing an ink imprint of the type directly onto the tape incident to such movement of the roller over the galley of type.

16. A printing device of the character described, comprising a main frame; a rotatable storage reel of paper tape; a rotatable rewind spool having driving connection with said storage reel; an impression roller; an auxiliary frame for supporting said roller, pivotally connected to the main frame on an axis normal to the axis of rotation of said roller with a portion of the roller projecting below the main frame, said tape from the storage reel being trained around the under portion of the roller and connected to the rewind spool, said reel and spool being simultaneously rotated to cause unwinding of the tape from the storage reel and winding it onto the spool incident to rotation of the roller by frictional move-

ment of the roller and tape over a galley of type; and means mounted on the auxiliary frame and serving to produce an ink imprint of the type directly onto the tape incident to such movement of the roller over the galley of type, said means comprising a support having projections at opposite sides of the main frame; a storage spool of ink-containing ribbon mounted on one projection; a rewind spool for the ribbon mounted on the other projection; and drive means interconnecting said ribbon spools whereby said ribbon is caused to be frictionally unwound from the storage spool and travel against the paper tape at the impression roller, and wound onto the rewind spool by the movement of the roller, with the paper tape and ribbon therebelow, over the galley of type.

17. A printing device of the character described, comprising a main frame; a rotatable storage reel of paper tape; a rotatable rewind spool having driving connection with said storage reel; an impression roller; an auxiliary frame for supporting said roller, pivotally connected to the main frame on an axis normal to the axis of rotation of said roller with a portion of the roller projecting below the main frame, said tape from the storage reel being trained around the under portion of the roller and connected to the rewind spool, said reel and spool being simultaneously rotated to cause unwinding of the tape from the storage reel and winding it onto the spool incident to rotation of the roller by frictional movement of the roller and tape over a galley of type, said main frame having portions extending at opposite ends of the impression roller; hand grips on said extensions of the main frame disposed in approximate alignment with the axis of rotation of said roller; and inking means mounted on the auxiliary frame and progressively contacting said tape as it travels under the roller for producing an ink imprint of the type directly onto the tape incident to such movement of the roller over the galley of type.

CLARENCE C. RUEBEL.
